to The Murray Corporation of America, De-
troit, Mich., a corporation of Delaware

Application March 21, 1944, Serial No. 112,985

Term of patent 7 years

(Cl. D91—3)

To all whom it may concern:

Be it known that I, Bertrand N. Trombley, a citizen of the United States, residing in Oak Park, in the county of Oakland, State of Michigan, have invented a new, original, and ornamental Design for a Faucet, of which the following is a specification, reference being had to the accompanying drawing, forming a part thereof, wherein:

Figure 1 is a perspective view of a faucet showing my new design, and

Figure 2 is a rear perspective view of the faucet illustrated in Figure 1.

What I claim is:

The ornamental design for a faucet, substantially as shown.

BERTRAND N. TROMBLEY.
